UNITED STATES PATENT OFFICE

158,903

STEERING WHEEL KNOB BASE

John Sinko, Oak Park, Ill.

Application March 5, 1949, Serial No. 1,234

Term of patent 14 years

(Cl. D14—30)

To all whom it may concern:

Be it known that I, John Sinko, a citizen of the United States, residing at Oak Park, county of Cook, and State of Illinois, have invented a new, original, and ornamental Design for a Steering Wheel Knob Base, of which the following is a specification, reference being had to the accompanying drawing, forming a part thereof, the dotted lines, however, being for illustrative purposes only, in which:

Figure 1 is an elevational view of the inner face of the steering wheel knob base showing my design; Fig. 2, an end elevational view; Fig. 3, an elevational view of the outer side of the base which engages the rim of a steering wheel; Fig. 4,

a top plan view; and Fig. 5, a bottom plan view of the same.

I claim:

The ornamental design for a steering wheel knob base, as shown and described.

JOHN SINKO.
